CLOCK CONTROLLED CONTACT MECHANISM

Robert E. McClure, Warren, Ohio, assignor, by
mesne assignments, to The Wean Engineering
Co., Inc., Warren, Ohio, a corporation of
Ohio

Application August 8, 1936, Serial No. 94,922

6 Claims. (Cl. 200—35)

This invention relates to mechanism for making and breaking control circuits at predetermined times, and in particular to mechanism for controlling a radio receiver having automatic tuning mechanism.

In the automatic operation of various devices, for example, the automatic tuning of a radio receiver, it is desirable to close and open the control circuits at predetermined times. While various clock-controlled contact mechanisms have been suggested heretofore, none of them with which I am familiar are particularly well suited for controlling a radio receiver. It is an object of my invention, therefore, to provide a time switch specially suited for controlling a radio receiver, although it may be used with other devices as well.

A complete understanding of the invention may be had from the following detailed description thereof referring to the accompanying drawing illustrating a present preferred embodiment. In the drawing,

Fig. 1 is a partial front elevation of a clock-controlled contact mechanism;

Fig. 2 is a sectional view along the line II—II of Fig. 1;

Fig. 3 is a partial sectional view along the line III—III of Fig. 2; and

Figs. 4 and 5 are sectional views similar to Fig. 3 showing the parts in different relative positions.

Referring now in detail to the drawing, the apparatus indicated generally at 10 is mounted within a case or cabinet having a front wall 11. This may be the cabinet of a radio receiver or a separate cabinet enclosing the control clock and mechanism only.

A supporting plate 12 is disposed rearwardly of the wall 11, and may be secured thereto by any convenient means, not shown. The wall 11 is provided with a circular window 13 wherein a clock dial 14 is disposed. A cup-like member 15 is mounted on the plate 12 concentric with the dial 14. An arbor 16 is journaled in a bearing 17 formed centrally of the cup 15, and is provided with a gear 18 whereby it may be driven. The gear 18 is adapted for cooperation with a clock drive of any desired type, mechanical or electrical, the member 15 being slotted at 19 to facilitate engagement between the gear 18 and the drive. An hour hand 20 is carried on the arbor 16.

A ring 21 is rotatable around the member 15, being seated on an annular bearing 22 carried thereon. The ring 21 is preferably of electrically conducting material, although this is not essential. The hour hand 20 carries a spring contact

23 which has sliding contact with the ring 21. The hand 20, furthermore, is sprung so that it is biased toward the dial. The ring 21 has a notch or recess 24 therein, and when the contact 23 on the hand 20 enters the notch 24, the outer end of the hand is deflected toward the dial, as indicated in Fig. 5. The contact 23 has a down turned tip 23'.

The periphery of the ring 21 is provided with gear teeth 25. A pinion 26 meshes with the teeth 25. Pinion 26 is mounted on a shaft 27 extending through the wall 11 and the plate 12, and having a knob 28 thereon whereby the ring 21 may be adjusted.

A shaft 29 is journaled in the arbor 16, but is insulated therefrom by a sleeve 30. The outer end of the shaft carries a contact hand 31 having a detent 32 engageable by the contact 23 of the hand 20, as shown in Fig. 4. The inner end of the sleeve 30 has a gear 33 thereon. The sleeve 30 is rigid with the shaft 29 and moves therewith. A pinion 34 is mounted on a shaft 35 having a knob 36 for operating the gear 33 and, therefore, the hand 31. A brush 37 mounted on an insulating post 38 makes contact with the ring 21. Similarly, a brush 39 makes contact with the shaft 29.

The operation of the device described above requires only that the contact hand 31 be positioned, by the adjusting knob 36, to the hour 30 when it is desired that the control circuit be closed. If the hand 31 is set at two o'clock, as shown in Fig. 1, the contact 23 on the hour hand will engage the detent 32 on the hand 31 at that time, and close any control circuit connected 35 to the brushes 37 and 39. The contact hand thereafter will move with the hour hand, maintaining the control circuit closed until the hands reach the recess 24 in the ring 21. At that time, because of its spring-bias, the hand 20 tends to drop to the extent permitted by the depth of the recess, interrupting the engagement between the contact 32 and the hand 20. The hand 20 may then move free of the hand 31, being restored to 40 its normal level by the gradual slope on the outgoing side of the recess 24. The control circuit is thus closed at the time for which the contact hand 31 is set, and opened at the time for which the recess 24 is set. The tip 23' on the contact 50 23 permits the pointer 31 to be moved past the hand 20 in the clockwise direction, if desired.

It will be seen from the foregoing that the invention provides a simple and inexpensive, yet effective and easily adjusted mechanism for caus-

55

ing control circuits to be closed and opened at predetermined times.

As already intimated, the ring 21 may be of non-conducting material. In such cases, the 5 brush 37 would have to engage the arbor 16 to make connection with the hand 20. Instead of mounting the pointer 31, the ring 21 and the knobs 27 and 35 on the clock face, they may be disposed on the back of the clock. In such construction, the knobs would require pointers and 10 dials, and an hour hand at the back of the clock would be needed to cooperate with the contact hand 31. This and other changes in the details of the construction of the preferred embodiment 15 of the invention illustrated herein by way of example, may be made without departing from the spirit of the invention or the scope of the appended claims.

I claim:

- 20 1. In a clock-controlled contact mechanism, a clock hand, a contact hand insulated from the clock hand but engageable therewith to close a circuit, and means adjustable about the path of the clock hand to cause the clock hand to separate from the contact hand.
- 25 2. A contact-timing mechanism comprising a contact finger rotatable about an axis to a predetermined position, a cooperating contact finger rotatable about said axis, insulated from the first-mentioned finger but engageable therewith to close a circuit, means for advancing said second-mentioned finger at constant rate, and means

adjustable about said axis for causing separation of the fingers at a predetermined time.

3. Contact mechanism comprising a moving contact traversing a predetermined path, a relatively fixed contact movable to any position in 5 said path whereby to be engaged by the moving contact for closing a circuit and move with it thereafter, and means adjustable in said path for causing separation of the contacts at a predetermined time.

4. Contact mechanism comprising a pair of pointers mounted for rotation about a common axis but insulated from each other, means for advancing one pointer into engagement with the other whereby a circuit is closed and the pointers 15 thereafter move together, and means adjustable about said axis for causing said one of said pointers to leave the other behind, breaking said circuit at a predetermined time.

5. The combination with a clock hand, of a 20 member normally engaged by said hand, a contact pointer adjustable to different positions in the path of said hand for engagement thereby at predetermined times, and means on said member to cause said hand to disengage said pointer, said 25 member being adjustable to different positions in the path of said hand.

6. The combination defined by claim 5 characterized by said pointer being above said hand, and said means comprising a depression into 30 which said hand moves to disengage the pointer.

ROBERT E. McCLURE.
